UNITED STATES PATENT OFFICE.

WINFIELD H. TABER, OF BOSTON, MASSACHUSETTS.

DESIGN FOR A CORNER-BLOCK FOR MATTRESS-FRAMES.

SPECIFICATION forming part of Design No. 26,244, dated November 3, 1896.

Application filed August 7, 1896. Serial No. 602,090. Term of patent 7 years.

To all whom it may concern:

Be it known that I, WINFIELD H. TABER, a citizen of the United States, residing at Boston, in the county of Suffolk and State of Massachusetts, have invented and produced a new and original Design for Corner-Blocks for Mattress-Frames, of which the following is a specification, reference being made to the accompanying drawing, showing a part thereof.

The drawing shows in perspective a corner-block showing my design.

The leading feature of my design consists in a rectangular box-like structure open at the top and at one side and having a depending arm, the end of which terminates with an annular or socket-like formation.

a b c d represent four sides of a rectangular box-like structure, and *f* represents the depending arm, terminating with the annular or socket-like formation *h*.

Several holes *i* appear in the side *a*, and also a thin rectangular block *j* projects from said side *a*.

I claim—

The design for corner-blocks for mattress-frames herein shown and described.

In testimony whereof I have signed my name to this specification in the presence of two subscribing witnesses.

WINFIELD H. TABER.

Witnesses:

B. J. NOYES,
HARRY O. ROBINSON.
